UNITED STATES PATENT OFFICE.

LOUIS HOFFMAN, OF DULUTH, MINNESOTA, ASSIGNOR, BY MESNE ASSIGNMENTS, TO STEAM PRESSING IRON COMPANY, A CORPORATION OF DELAWARE.

PRESSING MACHINE.

Application filed October 5, 1920. Serial No. 414,720.

To all whom it may concern:

Be it known that I, LOUIS HOFFMAN, a citizen of the United States, residing at Duluth, in the county of St. Louis and State of Minnesota, have invented certain new and useful Improvements in Pressing Machines, of which the following is a specification.

My invention relates to a machine for pressing garments of the type employing a heated flat iron or tailor's goose, which is movably suspended over the table or buck on which the garments are placed. A machine of this general character is shown in Patent No. 1,196,112, granted to me on August 29, 1916, reissued as No. 14,590 on February 11, 1919, and in Patent No. 1,404,859, granted to me Jan. 31, 1922.

One of the objects of the present invention is to make certain improvements upon the pressing machine as shown and described in said patents, said improvements comprising the provision of a lock for holding the operating table or buck in elevated position against the pressing iron, an improved locking mechanism for holding the buck against lateral movements, an improved mechanism for raising and lowering the buck, and other improvements whereby the construction of the machine is simplified and its operation facilitated.

A further object is to provide the machine, for certain operations, with a buck or pressing table or board of improved construction having a duct whereby the same may be heated by circulation of steam.

The invention is illustrated, in certain preferred embodiments, in the accompanying drawings wherein—

Fig. 1 is a front elevation of a pressing machine constructed in accordance with my invention, a portion of the machine being broken away and part being shown in section.

Fig. 2 is a fragmentary view taken on the section line shown on Fig. 1, looking in the direction of the arrows designated 2—2.

Fig. 3 is an inverted sectional plan on line 3—3 of Fig. 1.

Fig. 4 is an inverted plan view of the steam heated buck.

Fig. 5 is a plan view of the machine.

Fig. 6 is a partial vertical sectional view

on the section line of Fig. 1, looking in the direction of arrows 6—6.

Fig. 7 is a sectional view on line 7—7 of Fig. 6.

Fig. 8 is a fragmentary view, in perspective, of part of the operating treadle.

Fig. 9 is a view, in perspective, of the collar on the rock shaft of the machine by means of which the treadle is adjustably engaged with the rock shaft.

Fig. 10 is an inverted plan view of the parts illustrated in Figs. 8 and 9 shown as assembled with the rock shaft.

Fig. 11 is a fragmentary plan view illustrating the mechanism for holding the buck against lateral movement, and

Fig. 12 is an end elevation of the parts shown in Fig. 11.

Like characters of reference designate like parts in the several figures of the drawings.

Referring to the drawings, 25 designates the base portion of the frame of the machine on which is supported, on uprights 26 fixed in sockets 27 on the base, a rectangular structure consisting of a pair of inwardly facing channel irons 28 connected by end pieces 29, the structure being braced by bracing members 30, 31. A laterally moving carriage composed of inwardly facing channel irons 32 and end pieces 33 is provided with rollers 34 which operate in grooves 35 formed in the horizontal webs of the channel members 28. A second carriage 36, provided with rollers 37, is mounted so as to move forwardly and backwardly on the track provided by the channel members 32. The carriage 36 supports a rod 38 secured in a split sleeve 39 on the carriage and

clamped thereto by a screw 40 which has pivoted thereto a handle 41. On the lower end of the rod 38 is a ball 42 which enters a socket 43 formed in the top portion of the flat iron 44. The latter is provided with a handle 45 and is adapted to move in all directions over the pressing buck or table 46.

The buck or board 46 is preferably made of cast iron or other metal and is formed with a duct for circulation of steam for the purpose of heating the buck. The steam duct in the buck is preferably made by casting a pipe coil 47 into the same, the ends of which coil project from the casting and

are connected one with a flexible tube 48 for introduction of steam to the coil, and the other with a flexible tube 49 for discharge of steam or water of condensation therefrom. 5 The buck may be covered with a suitable cloth 50. Secured to the under side of the buck is a T-iron 51, the depending web of which fits into a groove in a saddle casting 52 secured to a carriage 53, the buck being 10 clamped to the saddle casting by means of a clamping strap 54, bolts 55 and nuts 56.

The carriage 53 is provided with rollers 57 which move in a track formed of a pair of channel irons 58, the horizontal webs of 15 which are preferably grooved to guide the rollers, these channel irons being secured to upstanding webs 59 on a pair of vertically movable upright members 60 arranged adjacent to upright members 61 on the base 20 frame 25 of the machine. By the means just described the buck can be given lateral movements with respect to the machine, because of the capacity for movement of carriage 53 on the track 58, and can be raised 25 vertically with the track in order that the work may be brought up against the iron. The buck is moved laterally by hand. It is raised by means of a treadle 62 and certain mechanism which will now be described. The 30 treadle comprises a lever 63, the inner end of which is forked as shown at 64 (Fig. 8) and is provided with a pair of arcuate bearings 65 adapted to engage with a rock shaft 66 mounted in bearings 67 in the base frame 35 of the machine. 68 (Fig. 9) is a collar fastened to rock shaft 66 between the forked ends of the treadle lever 63, the collar being formed with a lug 69 having a threaded opening for a set screw 70, the end of which 40 is adapted to bear against the treadle lever 63. 71 is a lock nut to hold the set screw at any desired position, the set screw being 45 adjustable for the purpose of varying the initial or normal position of the treadle for operators of different height. Secured to each end of rock shaft 66 is an arm 72 adapted to bear against one end of a lever 73 pivoted at 74 to the base frame of the machine. The other end of lever 73 bears 50 against a roller 75 (Fig. 7) on a shaft 76 which is secured adjustably, to the forked end 77 of one of the upright members 60 supporting the track on which the buck carriage runs. The upright members 60 are 55 formed near opposite ends with guide slots 78, 79 through which project studs 80, 81 secured to the frame members 61, spacing washers 82 intervening between the movable members 60 and the frame members 61. 60 Springs 83 are secured to each of the studs 81 and to studs 84 fixed to the movable members 60. These springs are stressed when the treadle is operated to raise the buck so 65 that they return the buck to normal position when the treadle is released. If the

buck should outweigh the treadle mechanism the springs should be arranged so as to be under tension when the buck is down, thereby counterbalancing the same as it is raised.

Under some circumstances, where the 70 nature of the pressing operation is such that the operator has sufficient time to operate several machines, it is desirable to lock the buck in elevated position against the iron. The operator after so locking one machine 75 is free to operate others in the same manner before returning to the first machine. Inasmuch as the iron is steam heated, there is no danger of burning the fabric which is 80 being pressed. For this purpose I provide a locking device associated with and operable in connection with the treadle. 85 (Fig. 2) is a member pivoted between ears 86 formed on the treadle lever 63, the upper end of said member being curved backwardly and formed with teeth 87 which are 85 adapted to engage with the lower edge of a transverse member 88 of the base frame of the machine. The member 85 has a lug 89 adapted to bear against the treadle to limit the backward movement of said member. 90 is another member pivoted between ears 86 having a foot piece 91 and provided with a stud 92 adapted to bear against member 85. 93 is a heavy spring extending from member 90 to member 85. 94 is a lighter spring connecting member 85 with the treadle. When the treadle 62 is operated without depressing foot piece 91, to raise and lower 95 the buck, the toothed portion 87 of member 85 clears the cross piece 88. If, however, the foot piece is depressed, member 85 will be pulled forwardly, spring 94 being lighter than spring 93, and the teeth 87 of member 93 will engage the cross piece 88 as soon as 100 the operator takes his foot from the foot piece 91. To actuate the footpiece 91 as the treadle 62 is operated, the operator might place the heel of the shoe on the treadle 62 and the sole on the footpiece 91 until the 105 treadle 62 had been depressed sufficiently whereupon the foot of the operator might be moved so as to clear the footpiece 91 while still holding down the treadle 62. To release the lock the operator presses down 110 on treadle 62. This disengages the teeth 87 from the cross piece and spring 94 reacts to return the parts of the locking mechanism to their normal position.

The carriage 53 is normally held from 115 lateral movement on the rails 58 by a preferably friction operating holding mechanism which is released when the carriage is to be moved. This mechanism is shown in detail in Figs. 2, 3, 11 and 12. Secured to the under side of rails 58 is a cross piece 120 95 formed with a perforated boss 96 for a stud 97 formed with a circular head 98 to which are pivoted on oppositely disposed studs 99 a pair of pins 100 which are guided 125 130

in lugs 101 formed on the cross piece 95, the extremities of the pins being preferably beveled and engaging depending webs 102 on the carriage 53. 103 is a lever provided at its outer end with a knee pad 104, the inner end of the lever extending through stud 97 and through a collar 105 thereon and held in place by a set screw 106. 107 is a spring fastened to a stud 108 on the lever 103 and to a stud 109 on the forward channel bar rail 58. This spring tends to rotate stud 97 in the direction to force the pins 100 against the webs 102 on the carriage. The operator, by pressing his right knee against the knee pad 104 and moving the same to the right, withdraws the pins 100 out of contact with said webs so that by movement of the buck the portion of the garment to be pressed may be brought to a convenient position in front of the operator. Thereupon the knee pad is released and the carriage locked in this position.

The operation of the machine is as follows: The garment to be pressed is placed upon the buck 46, which may or may not be steam heated, as desired. The operator can carry on the pressing operation while seated. To bring the work before him the operator presses his right knee against the knee pad 104, moving it to the right and releasing carriage 53 from the hold of the locking pins 100. When the work has been properly positioned the operator moves his knee from the knee pad 104 and the pins 100 engage the depending flanges 102 of the carriage so as to hold the carriage and buck in a stationary position. The buck is then raised, by pressing down on treadle 62, until the work is brought against the iron 44. The iron can be moved in any direction over the garment by means of its handle 45. At the same time the pressure of the iron on the work may be increased to the desired extent by depression of treadle 62. The buck may be held, if need be for the purpose above noted, in its elevated position by engagement of the locking rack 87 with the cross bar 88 of the frame of the machine through depression of the foot operated member 90. Depression of the treadle 62 will release the lock when the buck is to be lowered.

I claim:

1. A pressing machine comprising a frame, an ironing board on said frame, an iron supported from said frame and movable in a plane parallel with the face of said board, means comprising a foot lever for bringing the iron and the board into operative contact with each other, locking means for holding said iron and said board in operative pressing relation, and a second foot lever adapted by a downward stroke to move said locking means into operative locking position.

2. A pressing machine comprising a frame, an ironing board on said frame, an iron supported from said frame and movable in a plane parallel with the face of said board, means comprising a foot lever for bringing the iron and the board into operative contact with each other, locking means for holding said iron and said board in operative pressing relation, yielding means serving normally to hold said locking means out of operative position, and other means for moving said locking means against the action of said yielding means into operative locking position, said locking means being held automatically in continued locking position until released by further downward pressure upon said foot lever.

3. A pressing machine comprising a frame, an ironing board on said frame, an iron supported from said frame and movable in a plane parallel with the face of said board, means comprising a foot lever for bringing the iron and the board into operative contact with each other, a rack pivotally mounted on said foot lever and adapted by operative engagement with a part of said frame to hold the iron and the board in operative pressing relation, yielding means serving normally to hold said rack out of operative engagement with the frame, and a second foot lever for moving said rack against the action of said yielding means into operative locking position.

4. In a pressing machine, the combination of a frame, supporting means for the work, a pressing implement movably supported over said supporting means, mechanism for raising and lowering said supporting means comprising a treadle, a rack pivoted to the treadle and adapted to engage the frame of the machine to hold the supporting means in elevated position, and a foot operated device pivoted to the treadle to bring about said engagement.

5. In a pressing machine, the combination of a frame, supporting means for the work, a pressing implement movably supported over said supporting means, mechanism for raising and lowering said supporting means comprising a treadle, a rack pivoted to the treadle and adapted to engage the frame of the machine to hold the supporting means in elevated position, a foot operated device pivoted to the treadle, a heavy spring connecting the foot operated device to the rack, and a lighter spring connecting the rack with the treadle for the purpose described.

6. In a pressing machine, the combination of a frame, supporting means for the work, a pressing implement movably supported over said supporting means, a treadle, the depression of which raises said supporting means, a counterbalancing spring associated with the treadle, a segmental rack pivoted to the treadle adapted to engage the frame

of the machine to hold the supporting means in elevated position, a foot operated device pivoted to the treadle, a heavy spring connecting the rack with the foot operated device, a lighter spring connecting the rack with the treadle, and stops to limit the movements of the rack.

7. In a pressing machine, the combination of a frame, supporting means for the work, a pressing implement movably supported over said supporting means, a rock shaft in the lower part of the frame, an arm thereon, a lever pivoted to the frame and engaged by said arm, the other end of the lever being arranged to lift the supporting means, a treadle to operate the rock shaft, and a counterbalancing spring arranged to facilitate the movement of the supporting means.

20 8. In a pressing machine, the combination of a frame, supporting means for the work, a pressing implement movably supported over said supporting means, a rock shaft in the lower part of the frame, an arm thereon, a lever pivoted to the frame and engaged by said arm, the other end of the lever being arranged to lift the supporting means, a counterbalancing spring arranged to facilitate the movement of the supporting means, a treadle to operate the rock shaft, and adjusting means between the shaft and treadle to adjust the normal angular position of the latter.

9. In a pressing machine, the combination of a frame, supporting means for the work, a pressing implement movably supported over said supporting means, a rock shaft in the lower part of the frame, an arm thereon, a lever pivoted to the frame and engaged by said arm, the other end of the lever being arranged to lift the supporting means, a counterbalancing spring to facilitate the movement of said supporting means, a treadle having a bearing to engage the rock shaft, a collar on the shaft having a lug, and a set screw in the lug to engage the treadle.

10. In a pressing machine, the combination of a frame comprising a pair of upright members, supporting means for the work comprising movable upright members lying along the upright frame members, a pressing implement movably supported over said supporting means, a treadle, means associated with the treadle for engaging the movable upright members to raise the same, and springs interposed between and connected with said upright

frame members and the movable upright members adapted substantially to balance the supporting means and the treadle.

11. In a pressing machine, the combination of a frame, a track laterally extending with respect to the frame, a support for the work movable on said track, frictionally operating means for holding the supporting means in rigid position with respect to the track, and a lever adapted by an operative stroke to release said holding means.

12. In a pressing machine, the combination of a frame, a track laterally extending with respect to the frame, a support for the work movable on said track, means having frictional engagement with said supporting means for holding the same against such movement, and means comprising a member positioned to be controlled by the knee of the operator for releasing said holding means.

13. In a pressing machine, the combination of a frame, a track laterally extending with respect to the frame, a support for the work movable on said track, a rotatable element on the track, a member pivoted thereto and guided to engage said supporting means, a lever to rotate said element, and a spring to return the same to normal position.

14. In a pressing machine, the combination of a frame, a track laterally extending with respect to the frame, a support for the work movable on said track, a rotatable element on the track, a pair of members pivoted thereto, and guided to engage said supporting means to hold the same in fixed position, and means for rotating said rotatable element.

15. In a pressing machine, the combination of a frame, a track guided so as to have vertical movement on the frame, a carriage on the track, a rotatable element on the track, a pair of members pivoted to opposite sides of the rotatable element, a guide to engage the carriage, and a lever fixed to the rotatable element for turning the same.

16. In a pressing machine, the combination of a frame, a track guided so as to have vertical movement on the frame, a treadle and mechanism operated thereby to raise and lower the track, a carriage on the track, a buck, and means for removably attaching the buck to said carriage.

LOUIS HOFFMAN.
